CHARLES VIVION STUART, OF MEMPHIS, TENNESSEE, ASSIGNOR TO STUART AMERICAN PRODUCTS COMPANY, OF MEMPHIS, TENNESSEE, A CORPORATION OF TENNESSEE.

PROCESS OF ATOMIZING AND BURNING HYDROCARBONS.

1,164,139.

Specification of Letters Patent. Patented Dec. 14, 1915.

Application filed February 16, 1914. Serial No. 819,067.

To all whom it may concern:

Be it known that I, CHARLES VIVION STUART, a citizen of the United States of America, residing at Memphis, in the county 5 of Shelby and State of Tennessee, have invented certain new and useful Improvements in Processes of Atomizing and Burning Hydrocarbons, of which the following is a specification.

10 My present invention relates to a process of atomizing and burning hydrocarbons, and the process involves the admixing of air and hydrocarbon under pressure and subjecting it to successive compression and expansion 15 actions, the expansion immediately following the greatest compression, preferably in the presence of heat, expansion taking place within a combustion chamber which permits rapid action.

20 The preliminary admixture of the air and hydro-carbon is preferably provided in advance of the compression step, in any of several ways, the preferred manner being by forming what may be considered a stream 25 of the combined air and hydro-carbon and giving the stream a whirling action to deliver the combined mixture to a screen baffle in a direction angular to the face of the baffle and to the baffle axis. The baffle being 30 located at the entrance to the compression chamber, the direction of stream delivery relative to the baffle is such that the direction of contact is angular to the baffle axis, and the result is a breaking up and more 35 complete admixture of the combined air and hydro-carbons, this admixture being immediately compressed and then expanded in the presence of heat. The whirling action may be given in various ways, one form

40 being by the use of a spiral within a tube, the combined air and hydro-carbon being forced around the spiral by the pressure behind it. When this form is employed the convolution of the spiral adjacent the screen baffle, through its particular configuration, tends to increase this breaking up or atomizing condition. The delivery of the combined air and hydro-carbon angularly to the 45 face and axis of the baffle may also be provided by forming a tortuous passageway which has its exit adapted to give this angular direction to the stream; in this connection the passageway may be formed by

the use of a baffle or baffles of suitable configuration.

55 The hydro-carbon employed may be either the light or heavy oils.

The drawing accompanying this application shows one form of an apparatus for practising this process.

60 In said drawing, Figure 1 is a plan view, and Fig. 2 is a sectional view taken on line 2-2 of Fig. 1.

Referring to the drawings, 1 indicates a burner tube provided with an hydro-carbon (indicated generally as oil) inlet 2 and an air inlet 3. Near the other end of the tube is located a spiral 4, and between the spiral and the oil and air inlets is located a pressure-providing means such as a fan blower 65 5 adapted to force the combination of the oil and air around the convolutions of the spiral 4. The exit end of the spiral is preferably located at the entrance to a compression chamber 7, the wall of which is preferably cone-shaped with an opening 8 at the smaller end of the chamber, the latter being formed somewhat similar to a truncated cone, this chamber being preferably located at the end 6 of the tube 1. If desired, and 70 I preferably employ the same, I may provide a screen baffle 10 at the entrance to the compression chamber, the face of this baffle extending at right angles to the axis of the chamber 7, this baffle being also located at 75 the exit end of the spiral, the result being that the combined air and oil which is given a whirling action in being forced around the spiral convolutions is directed toward this screen baffle 10 in a direction angular both 80 to the baffle face and the baffle axis; consequently, the stream of air and oil not only has its direction of flow changed from the spiral to one approaching the direction of the axis of the chamber 7, but this change is 85 made through the baffle 10, the direction of flow toward the baffle tending to break up and atomize the stream and thus form a more intimate admixture of the combined air and oil immediately preceding its compression.

90 An enlarged, and preferably elongated combustion chamber 9 surrounds the end 6 of the tube and may be attached thereto in any convenient manner. Said chamber 9 95 may be of any appropriate material which

will not be greatly affected by intense heat, and may be lined with asbestos, fire-clay or other fire-resisting material. As will be seen the combustion chamber is open at its forward end to permit of the passage of the flame outwardly, the burning of the admixture taking place within the combustion chamber. This combustion has the effect of heating the walls of the chamber, and the intense heat, being at the point of expansion, causes a more rapid gasifying action, so that the gaseous product is in such a state as to provide for substantially perfect combustion, the flame resultant therefrom providing an intense heat upon its issuance from the combustion chamber. In this connection, the relative sizes of the parts become of some importance, the diameter of the combustion chamber being preferably about double that of the tube 1 and about four or five times that of the restricted exit opening 8.

The general operation of the structure shown in the drawing appears obvious. The hydro-carbon enters through the inlet 2, preferably under a pressure sufficient to cause it to be introduced into the tube in the rear of the fan which also draws in air through the inlet 3. The air takes up the hydrocarbon and the combination is forced into the spiral passage under the pressure provided by the rotation of the fan, this pressure, after the fan has reached the desired speed, remaining constant and causing a constant supply to the spiral passageway. After traversing this passageway, within which there may be an atomizing effect, due to the form of the spiral, the combined air and hydro-carbon passes through the baffle 10 into the compression chamber 7 from which it is discharged through the restricted opening 8, into the combustion chamber 9. As will be understood, the compressed mixture, being under the pressure of the stream, like constant supply will be forced through the opening at an increased velocity, which is immediately and suddenly reduced by the

expansion which at once follows the discharge through the restricted opening. This action causes the combined elements to more nearly approach complete atomization, and gasification of the finely atomized mixture is materially assisted by the heat of the combustion chamber, producing a highly inflammable mixture at the point of combustion. As this state is reached after the mixture passes through the opening 8 it will be readily understood that the combustion takes place practically entirely within the combustion chamber. Furthermore, the usual reverberation is eliminated.

It will be obvious that, while I have shown a preferred form of apparatus for carrying out this process, various modifications thereof will be suggested to those skilled in the art to which the invention appertains. Such modifications and changes as may be required or desired in carrying out the principles of my invention are reserved, in so far as the same may fall within the spirit and scope of the invention as expressed in the accompanying claim.

What I claim as new is:

The process of atomizing and burning hydrocarbon, which consists in inducing a current of air and oil under pressure into a relatively restricted passage, causing said mixture to travel in a tortuous path, forcibly directing the mixture at an angle against a member in the path thereof, whereby atomization is promoted, thereafter compressing said mixture, thereby increasing the speed of said mixture, thereafter materially reducing the speed of said mixture in the presence of heat, whereby further atomization and gasification is assisted, and thereafter burning said mixture.

In testimony whereof I affix my signature in presence of two witnesses.

CHARLES VIVION STUART.
